UNITED STATES PATENT OFFICE.

GEORGE MORSE GUILD AND BYRON CAVIS BURNHAM, OF BOSTON, MASS.

PIANO-FORTE.

SPECIFICATION forming part of Letters Patent No. 336,565, dated February 23, 1886.

Application filed March 30, 1885. Serial No. 160,632. (No model.)

To all whom it may concern:

Be it known that we, GEORGE MORSE GUILD and BYRON CAVIS BURNHAM, of Boston, in the county of Suffolk, of the Commonwealth 5 of Massachusetts, have invented a new and useful Improvement in Piano-Fortes; and we do hereby declare the same to be described in the following specification and represented in the accompanying drawings.

10 Figure 1 is a top view of part of the frame and sounding-board of a piano-forte, and some of the main and some of the auxiliary strings, and the devices, as hereinafter described, for supporting such strings. Fig. 2 is a trans- 15 verse section on the line $x y$ of Fig. 1. Fig. 3 is a side view of the main bridge as exhibited in Fig. 1. Fig. 4 is a cross-section of one of the auxiliary bridges F and its adjustable bar G, such section exhibiting the manner in which 20 a string, S', crosses the bridge and the bar, and extends under and against the latter.

The nature of our invention is defined in the claims hereinafter presented.

In the said drawings, A denotes part of the 25 wooden frame, and B part of the iron or string-supporting frame, of a piano-forte. C represents the sounding-board, and D the metallic bridge, across which the series of main strings extend. The said bridge does not, through- 30 out its entire length, rest upon the sounding-board, it being for a short distance from its end, as shown, raised above and out of contact with such board, and there fixed to a bracket, E, that extends laterally from it, (the said 35 bridge,) as shown by dotted lines in Fig. 1 and in full lines in Fig. 2. The bracket near its rear end extends downward, or has a flange projecting down from it, as shown at a in Fig. 2, such flange resting on and being fast- 40 ened to the sounding-board. The bracket is of metal and cast in one piece with the bridge. By thus having part of the bridge out of contact with the sounding-board and supported by a bracket projecting from such part of the 45 said bridge, underneath the iron frame B and nearly to the next adjacent bridge of the auxiliary strings, it is found in practice that the sounding-board has more freedom of vibration, and a better tone of the strings results. Each 50 of the main strings S at its middle is hitched

upon a hitch-pin, such hitch-pins being represented at $a' b' a' b$, &c., in Fig. 1. Furthermore, each string has three bearings or supports, $c d e$, that are stout metallic standards projecting upward from the bridge. The 55 string goes through holes in the two outer bearings, c and e , and over and upon the top of the intermediate bearing, d , which is a little above such holes. (See Fig. 3.) The bearings c of each next succeeding string extends 60 laterally between the bearings c and d of the next preceding string, whose bearings d and e also extend laterally between the bearings c and d of the said succeeding string, such bearing to have each string apart from the next 65 one a distance equal or very nearly equal to the distance between the two parallel parts of such string. The bearings of each string should not touch the next preceding string. The auxiliary strings S' extend above and 70 cross the main string S, as usual in piano-fortes. The hitch-pins of the strings S' are shown at $a^2 a^2$, &c. There are a series of short bridges, F, to such strings S'. Each of such bridges goes down through the iron frame B 75 without contact therewith and rests upon and is fastened to the sounding-board C. (See Fig. 2.) Each bridge F has two bearing-flanges, h , extending upward from it parallel to each other and at a short distance apart. 80 Midway between each pair of such flanges is a bar, G, down through which headed screws i go and screw into the bridge. The strings S' rest upon the tops of the two flanges $h h$, and go under and across the bar G, and bear up- 85 ward against such bar.

From the above it will be seen that by means of the screws the pressure of the bar on the string may be increased or diminished, so as to vary somewhat the tones of the strings ex- 90 tending under it, all of which are advanta- geous in tuning the instrument or keeping it in proper tune.

We claim—

1. The combination of the bridge D, raised 95 at and near its end out of contact with the sounding-board, with a bracket, E, extending laterally from the part so raised out of contact with the sounding-board and nearly to the next adjacent bridge F, and having a flange 100

or projection to extend down to the sounding-board and fixed thereto, all being substantially as represented.

2. The auxiliary bridge F, having two double flanges, substantially as described, and resting on the sounding-board by the flanges only, in combination with the strings and the bar G, sustained upon the web of the bridge

by an adjusting screw, as and for the purpose described.

GEORGE MORSE GUILD.
BYRON CAVIS BURNHAM.
